CLAIM

The ornamental design for a handle, as shown and described.

DESCRIPTION

FIG. 1 is a perspective view of a handle incorporating our new design, showing an exemplary rip cord attached;

FIG. 2 is a perspective view of the handle incorporating our new design, showing the exemplary rip cord and an exemplary wheel attached;

FIG. 3 is a front orthogonal view of the handle incorporating our new design;

FIG. 4 is a back orthogonal view thereof;

FIG. 5 is a right orthogonal view thereof;

FIG. 6 is a left orthogonal view thereof;

FIG. 7 is an enlarged scale top orthogonal view thereof; and, FIG. 8 is an enlarged scale bottom orthogonal view thereof.

The broken lines showing the rip cord and wheel are included for the purpose of illustrating environmental structures and form no part of the claimed design.
